UNITED STATES PATENT OFFICE

MAXWELL H. SPREEN, OF DETROIT, MICHIGAN

REFRIGERATING MECHANISM SUPPORT AND CABINET THEREFOR

Application filed June 16, 1927. Serial No. 199,213.

My invention relates to mechanically refrigerated food storage cabinets, and more particularly to cabinets in which mechanical refrigerating mechanism is mounted within the casing.

An object of my invention is to provide a self contained mechanically refrigerated cabinet in which the mechanical refrigerating apparatus can be readily associated or removed **10** as a unit.

A further object of my invention is to provide a self contained mechanically refrigerated cabinet having relatively isolated refrigerated and machinery chambers with **15** which a unitary refrigerating apparatus is laterally movable relative thereto so that the evaporator will extend into the refrigerated chamber and the operating mechanism will extend within the machinery chamber.

20 Still another object of my invention is to provide a supporting frame, for mounting the evaporator and machinery of mechanical refrigerating apparatus in separate chambers of a refrigerator which encloses the refrigerant connections between the evaporator and machinery interiorly of a refrigerator.

Other objects of the invention, more or less incidental or ancillary to the foregoing will appear in the following description **30** which sets forth in connection with the accompanying drawings a preferred embodiment of the invention.

In the accompanying drawings:—

Figure 1 is a front elevation of a mechanically refrigerated refrigerator embodying **35** my invention.

Figure 2 is a section of the same, taken on line 2—2 of Fig. 1, and

Figure 3 is a section of the same, taken on **40** line 3—3 of Fig. 1.

Referring to the drawings by characters of reference, 11 represents a refrigerator having superposed isolated compartments 12 and 14, the upper refrigerated compartment 12 receiving the cooling unit 13 of a mechanical refrigerating apparatus and the compartment 14 being insulated from the refrigerated compartment to receive the machinery of the mechanical refrigerating apparatus. **45** The compartments have lateral openings on

the same side of the refrigerator and are separated by the partition 16, the front edge of which is provided with recesses 17. Suitable movable closure members 10 are provided to close the lateral openings in the refrigerator leading to the interior compartments. **55**

The entire mechanical refrigerating apparatus is carried upon a supporting frame which is independent of and movable laterally relative to the refrigerator. The supporting frame includes a base 19, a pair of uprights, such as tubes 20, which are secured to the base and evaporator supporting arms 18 which are secured adjacent the upper ends of the tubes 20. The base 19 has mounted thereupon the major portion of a compressor-condenser-evaporator refrigerating apparatus, and directly supports all of the apparatus excepting the cooling unit, expansion valve, refrigerant conduits and the thermostat control which are directly carried by the tubes 20. A compressor 21, a driving motor 30 and the transmission belt 31 extending therebetween are carried directly by the base 19. Likewise the condenser 24 and a cooling fan (not shown) are also carried by the base. **60** **65** **70**

The upright tubes 20 of the support are utilized to enclose the major portion of the refrigerant return conduit 23, which extends from the vaporizer 32 to the compressor inlet 22, and the refrigerant feed conduit 28 which connects the expansion valve mechanism 29 with the condenser outlet. A conduit 9 extends from the compressor outlet 26 to the condenser inlet 25 completing the refrigerant circuit. **75**

The cooling unit 13 is carried by the upper end of the upright tubes and the arms 18 which extend therefrom, and consists of a brine tank 32 within which the evaporator coils 8 are arranged to surround a flue 35 for receiving an ice forming pan. The expansion valve 29 is carried by the cooling unit **80** and connects the inlet end of the evaporator with the feed conduit 28. A thermostat 33 is also supported by the cooling unit, and is suitably connected with conventional mechanism (not shown) for automatically con- **85** **90** **95** **100**

trolling the motor 30. A drain tray 36 projects from the standards 20 beneath the cooling unit to catch condensation, and is associated with the drain pipe 37 which leads 5 the condensation exteriorly of the refrigerator in any conventional manner.

The refrigerating apparatus herein described is of the conventional automatically operating compressor-condenser-evaporator 10 type and a further description of the operation thereof to refrigerate the compartment 12 is not deemed necessary to understand the invention. The refrigerating mechanism is carried entirely by the supporting frame 15 and can be laterally moved through the openings leading to the compartments when the closure members 10 are removed or opened. The upright tubes 20 can be moved into the recesses 17 in the partition 16 so that the 20 supporting frame can be moved laterally interiorly of the refrigerator, and plugs 38 are associated with the tubes 20 to enclose the space in the recesses intermediate the tubes and the partition so that the compartments 25 12 and 14 will be isolated relatively.

It will be seen that the evaporator is secured to the supporting frame in a plane above the machinery portion of the refrigerating apparatus, so that it can be located 30 in the refrigerated compartment while the machinery will be located in the machinery compartment. It will also be seen that the entire refrigerating apparatus is removable from the refrigerator, and that the refrigerant conduits are substantially enclosed by 35 a portion of the supporting frame.

Various changes can be made in the construction described without departing from the spirit of my invention and the scope of 40 what is claimed.

What I claim is:

1. A self contained mechanical refrigeration unit comprising a cabinet having a refrigerated compartment and a refrigerating mechanism compartment, mechanical refrigerating apparatus comprising refrigerant expansion means adapted to be disposed in said refrigerated compartment and refrigerant compressing mechanism adapted to be disposed in said mechanism compartment, a frame independent of said cabinet comprising a base on which said refrigerant compressing mechanism is assembled and uprights unitary with said base on which said refrigerating apparatus is assembled, all as a unit, said cabinet and said frame being so constructed and arranged as to permit said frame to be then inserted into said cabinet with said apparatus thereon.

60 2. A self contained mechanical refrigeration unit comprising a cabinet having a refrigerated compartment and a refrigerating mechanism compartment, mechanical refrigerating apparatus comprising refrigerant expansion means adapted to be disposed in said

refrigerated compartment and refrigerant compressing mechanism adapted to be disposed in said mechanism compartment, a partition between said compartments having recesses at its front edge, a frame independent of said cabinet comprising a base on which said refrigerant compressing mechanism is assembled and uprights rigidly secured to said base on which said refrigerating apparatus is assembled as a unit, said cabinet and said frame being so constructed and arranged as to permit said frame and assembled apparatus to be then inserted into said cabinet with said uprights disposed in the recesses of said partition.

3. A self contained mechanical refrigeration unit comprising a cabinet having superposed compartments open at one side; a unitary mechanical refrigerating apparatus including a frame entirely supporting an evaporator and machinery in different elevations for association with different compartments, said apparatus being removable laterally from said cabinet, and a movable closure for closing the opening leading to the refrigerated compartment.

4. A self contained mechanical refrigeration unit comprising a cabinet having thermally isolated compartments, a support extending into said compartments, an evaporator carried by said support within one of said compartments, compressor-condenser mechanism carried by said support in another of said compartments, and refrigerant conduit means extending from said evaporator to said compressor-condenser mechanism, said support enclosing the major intermediate portions of said refrigerant conduit means.

5. The combination with an insulated refrigerating compartment having a machine compartment associated therewith, of a machinery base arranged within the machine compartment, a refrigerant condensing unit rigidly secured to and supported by said base, a rigid refrigerant evaporating unit supported connected to said base and projecting laterally therefrom into the aforesaid insulated refrigerating compartment, a refrigerant evaporating unit arranged in the refrigerating compartment in the path of circulating air therein, said evaporating unit being rigidly secured to and entirely supported by the aforesaid support, and means disposed internally of the aforesaid support for connecting the evaporating unit with the condensing unit for the circulation of refrigerant fluid therebetween.

6. The combination with an insulated refrigerating compartment having a horizontally disposed wall and a door opening, of a notch projecting into the horizontally disposed wall immediately adjacent the aforesaid door opening, a machine compartment arranged externally of the refrigerating compartment beyond the horizontally dis-

posed wall, a machinery base arranged within the machine compartment, a refrigerant condensing unit secured to and supported by the latter, a refrigerant evaporating unit supported rigidly secured to the aforesaid base and projecting into the interior of the refrigerating compartment through the notch in the horizontally disposed wall, a refrigerant evaporating unit rigidly secured to and supported in the interior of the refrigerating compartment by the aforesaid support, and means projecting longitudinally of the support and disposed inside the peripheral limits of the latter for circulating refrigerant fluid between the evaporating and condensing units.

7. The combination with an insulated refrigerating compartment having a horizontally disposed wall and a door opening, of a notch projecting into the horizontally disposed wall immediately adjacent the aforesaid door opening, a machine compartment arranged externally of the refrigerating compartment beyond the horizontally disposed wall, a machinery base arranged within the machine compartment, a refrigerant condensing unit secured to and supported by the latter, a refrigerant evaporating unit supported rigidly secured to the aforesaid base and projecting into the interior of the refrigerating compartment through the notch in the horizontally disposed wall, a refrigerant evaporating unit rigidly secured to and supported in the interior of the refrigerating compartment by the aforesaid support, and means for circulating refrigerant fluid between the evaporating unit and the condensing unit, said evaporating unit, condensing unit, machinery base, and evaporating unit support being insertible into and removable from the refrigerating and machinery compartments by movement in planes parallel to the aforesaid horizontally disposed partition.

8. The combination with an insulated refrigerating compartment having a plurality of vertically disposed walls closed by horizontally disposed walls at opposite ends of the latter, a machinery compartment arranged externally of the refrigerating compartment beyond one of the aforesaid horizontally disposed walls, a refrigerant condensing unit disposed in the machinery compartment, a refrigerant evaporating unit disposed in the refrigerating compartment, a rigid support extending in close proximity to one of the walls of the refrigerating compartment, and means for securing the refrigerant condensing and evaporating units rigidly to the support adjacent the opposite ends thereof.

60 In testimony whereof I hereunto affix my signature.

MAXWELL H. SPREEN.
